WINDOW CONSTRUCTION

Stewart J. Dautrick, Detroit, and Owen L. Dautrick, Ferndale, Mich., assignors to Lewis G. Erb and Arthur E. Blow, both of Royal Oak, Mich.

Application August 29, 1940; Serial No. 354,636

5 Claims. (Cl. 20—12)

The present invention relates in general to a window construction and is in particular concerned with improved means whereby a window sash may be slidably mounted in a window frame of standard construction and the usual pulleys, sash cords and counterbalancing weights eliminated.

It is a primary object of the herein-described invention to provide a window construction of such type in which the sash guiding and supporting elements are mounted in a standard window frame without changes therein, thus enabling the application of the present invention to existing as well as newly installed windows.

A further object is to provide an improved window construction in which the sash may be quickly and easily removed, when desired, to permit cleaning the outside of the window glass, repainting et cetera, but in which the sashes are normally retained against removal.

Another object of the invention is to provide improved slide rails for engaging the opposite sides of the window sash, wherein springs are utilized for urging a sash supporting rail against the sash, these springs being so arranged and constructed as to permit their being wholly contained within the rail, when they are fully compressed.

Another object of the invention is to provide in spring urged slide rails for a window sash, improved means for anchoring the springs to the rail, which will not only enable variation of the number of springs at any desired portion of the rail, but also permit movement of the springs along the rail to vary their relative positions, whereby the pressure exerted against the sash at different portions of the rail may be varied to meet different operating and installation conditions.

A still further object of the invention is to provide in windows of the herein-described type, an improved weather strip arrangement to prevent infiltrations around and past the sash supporting slide rails, and wherein weather strips may be utilized as a latching medium to prevent removal of the sash, when the sash is in closed position.

Still another object is to provide as an article of manufacture a sash slide rail of improved construction.

Other objects and features of the invention will more fully appear from the following detailed description taken in connection with the accompanying drawing which illustrates a single embodiment thereof, and in which:

Figure 1 is a front elevational view of a window

embodimenting the present invention with parts broken away and parts shown in section;

Figure 2 is a sectional view with certain of the parts broken away to show details of construction, taken substantially on line II—II of Figure 1;

Figure 3 is an enlarged fragmentary sectional view of the same, taken substantially on line III—III of Figure 1; and

Figure 4 is a portion of a sectional view similar to Figure 3 on enlarged scale illustrating the relative positions of the sash and sash slide rail to enable removal of the sash from the frame.

As shown on the drawing:

15 For purposes of illustration, we have shown in the drawing one embodiment of the present invention, wherein the invention is applied to a window frame of standard construction having the usual sill 10 and upper rail 11 which are interconnected by the usual side frames or uprights 12—12. Along the innermost edge of each upright, the upright has secured thereto a molding stop 13, and along the opposite edge of the upright there is provided the usual blind stop 14. 20 Such stops are standard construction in window frames and cooperate to form guideways for the window casing in the ordinary installations.

In the present invention, advantage is taken of this construction and these guideways are utilized for the sash slide rails 15 and 16 which are so constructed and so mounted therein as will hereinafter be explained.

The guide rails are of duplicate construction, being cut to the proper length to fit between the 35 sill 10 and the head rail 11. For a double sash window, two rails are disposed between the molding stop and the blind stop, as shown in Figure 3, these rails being disposed with their opposite edges adjacent. Each rail is formed from an initially flat strip of rust-proof metal which is deformed in any suitable manner to provide on its inner face a longitudinally extending groove 17 which in this instance is shown as being of right angled construction in cross-section. At each 40 edge of the groove, the strip is looped to form laterally disposed ribs or tongues 18 and 19, and thence carried rearwardly of the bottom of the groove to form the opposite side walls 20 and 21 of the rail. The side walls have their rear marginal end portions inwardly deflected to form flanges 22 and 23 which lie in the same plane and are spaced apart and also spaced from the bottom portion of the groove 17 to provide in effect a T-shaped groove 24 on the rear face of the rail.

Figure 1 is a front elevational view of a window

The slide rails are secured in positions extending longitudinally of the uprights by means of suitable screws or nails 25, the heads of which are disposed in countersunk portions 26 of the bottom of groove 17. These countersunk portions are provided preferably adjacent the upper and lower ends of the rail and at an intermediate point between the rail ends, the intermediate countersunk portion and the countersunk portion at the uppermost end of the rail being spaced apart a slightly greater distance than the height of the sashes to be accommodated in the window. The rail thus is slidably mounted on the nails or screws for movement toward and away from the upright to which it is secured, and by adjusting the levels of the screw heads, the outward movement of the rails may be regulated.

The rails are normally urged outwardly by means of conical-shaped coiled springs 27 which are anchored to the rail by disposing the end thereof having the coil of greatest diameter within the T-shaped slot 24. The largest coil of the spring abuts against the inner surface of the material forming the bottom of groove 17 and is of such diameter that it closely and tightly engages the inner surface of the wall portions 20 and 21 of the rail to normally retain the spring in a desired position on the rail. By constructing the coil springs of conical shape, they may be completely compressed within themselves, and when so compressed completely contained within the T-shaped groove of the slide rail so as not to interfere or limit the movement of the rail toward the upright to which it is secured.

Ordinarily, three to five springs will be sufficient for each rail depending upon its length. In mounting each rail, it has been found desirable to provide at least three springs which are fixed as to position longitudinally of the rail, and for such purpose the fixed springs may be disposed in concentric relation around each of the countersunk portions 26 so that the rail securing screw will extend therethrough.

Where it is found necessary to secure additional spring pressure, or where it is desired to have greater spring pressure at certain portions of the rail than at other portions, the additional springs are anchored in the manner previously described and may be moved along the rails to the desired portion thereof, and the springs disposed in any desired spaced relation. The friction between the large coil of the spring and the walls 20 and 21 of the channel is sufficiently great to retain the spring in position and prevent its moving downwardly along the rail with which it is associated.

The springs are normally, when a sash is mounted in position, under compression to retain the slide rails in snug engagement with the side faces of the sash. The sash, is of the usual construction comprising side rails 28 and 29, each of these side rails being formed with lateral grooves 30 and 31 for receiving the side ribs or tongues 18 and 19 of the slide rail, the portion of the side rail of the sash lying between the grooves 30 and 31 defining a projecting portion 32 which will fit into the sash receiving groove 17 of the slide rail.

When the sash is in position, the springs 27 act to urge the slide rail into snug engagement with the sash and thus form a leak-proof arrangement which will serve to prevent the infiltration of wind, rain, dust and the like and also serve to prevent rattling of the window regardless of the position to which it is raised.

In order to prevent the entrance of dust and

the like between a slide rail and its associated upright, a weather strip 33 of angular cross-section may be secured to the inner face of the associated upright 12 either by separate nails or screws, or by the nails or screws utilized for mounting the slide rails in position. One leg 33' of this weather strip is disposed so as to project between the adjacently disposed edges 20 and 21 of the rails on each side of the window frame for supporting and guiding the upper and lower sashes thereof.

For further weather-proofing the window structure, standard weather strips 34 of the upstanding type may be provided for the top of the upper sash and the bottom of the lower sash, the slide rails and sashes being suitably notched to receive the strips therein when the sashes are in fully closed position.

It will be noted that the use of sash weights and cords have been entirely eliminated with our improved construction as described, and the sash may be easily moved upwardly and downwardly to any desired position. Moreover, the slide rail urging springs may be of any desired number and adjusted longitudinally of the slide rails to apply more or less pressure in different parts of the rails, for example, adjacent the top portions of the rails for holding the sashes in raised position.

With the nails or screws 25 placed in the manner previously described, the sashes in closed position will overlie one of the screws or nails. The only position in which this is not so is when the sashes are moved so as to lie between the intermediate and uppermost screws or nails 25 of the slide rails, these particular screws being spaced apart a slightly greater distance than the height of the sashes.

In order to remove the sash from the frame, it is only necessary to force the sash and one of the movable slide rails in one direction, while at the same time the other movable slide rail is pushed back in the opposite direction. This will enable removal of the sash, providing the sash is at a position between the intermediate and uppermost securing screws of the slide rails. At other position of the sash, the heads of the securing screws or nails holding the slide rails will prevent sufficient movement of the slide rails to give the proper clearance for removal of the sash.

In addition, it will be apparent that when the sashes are in closed position, the weather strip 34 also acts to retain the sashes against removal, even though the slide rails are moved sufficiently to give the proper removal clearance for the sash.

It is believed obvious that a window construction formed in this manner will be easily installable in a standard window frame at considerable saving at labor and that the various advantages referred to will be effected.

While we have illustrated and described the preferred form of construction, we do not wish to limit ourselves to the precise details of structure shown, but desire to avail ourselves of such variations and modifications as may come within the scope and spirit of the appended claims.

We claim as our invention:

1. A hollow slide rail for sliding engagement with an edge of a sash, said slide rail comprising a strip bent to define an elongate hollow member having a front face to engage an edge of a sash and to define forwardly extending and spaced opposed shoulders merging with rearwardly extending portions of the strip which define spaced opposed side walls terminating in

spaced opposed lips and with said spaced lips defining an elongated slot therebetween, and spring means entered in said hollow rail and engaging said side walls to retain said spring means in assembled relation to said rail.

2. A hollow slide rail for sliding engagement with an edge of a sash, said slide rail comprising a strip bent to define an elongate hollow member having a front face to engage an edge of the sash, and to define rearwardly extending and spaced opposed side walls having means defining an elongated slot between said walls, and a spring entered in said hollow rail and extensible through the slot, said spring having means frictionally engageable with said walls to retain a portion of said spring within said hollow member and slidably in said rail.

3. A hollow slide rail for engagement with an edge of a sash, said slide rail comprising an elongate hollow member having a front portion formed to define a pair of spaced and forwardly extending shoulders with a groove therebetween to guidedly receive an edge portion of a window sash, said rail being also formed to define a pair of spaced opposed and rearwardly extending channel elements terminating in a pair of oppositely directed and opposed lips spaced to define a slot therebetween, and a coiled spring having a portion of greater diameter than the width of said slot entered in said rail and between said channel elements.

4. A window construction comprising a window frame, a pair of elongate hollow sash rails

mounted side by side on a side of said frame, each of said sash rails comprising a member having a front portion formed to define a pair of spaced and forwardly extending shoulders with a groove therebetween to guidedly receive an edge portion of a window sash, and also being formed to define a pair of spaced opposed and rearwardly extending channel elements terminating in a pair of oppositely directed and opposed lips, and an L-shaped member having one leg disposed between said sash rails and having its other leg disposed rearwardly of a lip of one of said rails.

5. A window construction comprising a window frame, a pair of elongate hollow sash rails mounted side by side on a side of said frame, each of said sash rails comprising a member having a front portion formed to define a pair of spaced and forwardly extending shoulders with a groove therebetween to guidedly receive an edge portion of a window sash, and also being formed to define a pair of spaced opposed and rearwardly extending channel elements terminating in a pair of oppositely directed and opposed lips, and an L-shaped member having one leg disposed between said sash rails and having its other leg disposed rearwardly of a lip of one of said rails, and spring means inserted in said one of said rails and seated on the other leg on said L-shaped member.
